UNITED STATES PATENT OFFICE.

STERLING LEEO, OF LOS ANGELES, CALIFORNIA.

RAILROAD-TRACK CONSTRUCTION.

1,054,852.

Specification of Letters Patent.

Patented Mar. 4, 1913.

Application filed November 5, 1912. Serial No. 729,561.

To all whom it may concern:

Be it known that I, STERLING LEEO, a citizen of the United States, residing at Los Angeles, in the county of Los Angeles and 5 State of California, have invented a new and useful Improvement in Railroad-Track Constructions, of which the following is a specification.

This invention relates to railway track 0 constructions and particularly to tracks located on paved streets, and the principal object of the invention is to provide a structure adapted to be placed along the longitudinally extending sides of a rail that may 5 be readily removed to expose the rail fastening means, whereby a worn or useless rail may be instantly replaced by a new one without the necessity of tearing up and replacing permanent paving.

10 It is also an object to provide means for supporting the paving adjacent the rail so that the same can be readily removed without undue expense and labor.

In the drawings accompanying this specification Figure 1 is a transverse section through one rail of a track showing the relation of the improvement to the supporting ties for the track. Fig. 2 is a plan view of the improvement as applied to one interval between two supporting ties, the bricks not being shown. Fig. 3 is a detail perspective of a bracket used for the inner side of the rail. Fig. 4 is a similar view of a bracket normally used on the outer side of 35 the rail. Fig. 5 is a cross section of a modified form of a rail which may be used for this purpose.

Heretofore in the repairing of street tracks where the paving has been carried 40 across to the rail and embedding the latter, repairs to the rail and adjustment necessary on the tie plates or bonding means required the destroying of the pavement resulting in considerable loss of material.

45 This invention overcomes the above objections by providing a conduit which is bridged by suitable supporting means on which the usual vitrified brick may be laid and rigidly supported thereon in a position 50 to be easily removed to expose the rail and its fastenings.

The same numerals indicate like parts in the different views, 6 designating a rail having a head with the lateral sides 7 and 8, together with the flange 9 and the base 10 of the well-known railroad cross section. To

support this rail in proper relation is shown the common form of tie 11, the rail being fastened thereto by the usual spikes 12.

Spiked on the ties 11 parallel with the 60 rail, are the angularly formed walls 14 which are preferably provided with a flange 15 extending outwardly toward the rail and the shoulder 16 formed in the wall on the flanged side, the outer face 17 being preferably plane and of such height as to reach to the normal surface of the paving 18, forming a permanent wall for the latter and a protection to the inner edge thereof. The flange 16 on this wall is preferably provided 70 with the spike holes 19 through which the wall may be secured by the spikes 20.

The rail 6 commonly in use at present, is provided with the brackets 22 and 23, the form of bracket 22 being preferably used 75 where it is desired to form a groove adjacent the rail, this bracket being provided with the angled arm with supporting face 28 preferably projecting at right angles to the flange engaging face 24, through which 80 is carried the bore 25.

Oppositely disposed from the bracket 22 is preferably placed the bracket 23 also provided with an arm 26 extending at right angles to the flange engaging face 27 provided 85 with the bore 28. Bores 25 and 28 are adapted to register with the bore in the flange 9 of the rail, each of the brackets being secured by the bolt 29, being held in close engagement with the flange 9, the 90 lower edge resting on the base 10.

The bridge plates 30 and 31 are preferably of different form, plate 30 being provided with a horizontal portion and a vertical wall on which is formed the flange 32 which 95 abuts against the lateral face 7 on the rail providing the groove to receive the flange on the car wheel, the vertical wall 33 being preferably carried to such a height above the flange 32 that the brick 35 supported 100 thereon will form a flush surface with the tread of the rail and the paving 18 adjacent thereto.

The bridging plate 31 is a plane angular roll of metal as are the rails and the walls 14, this plate 31 resting upon the arm 26 and the shoulder 16 with its vertical wall 36 adjacent the outer side 7 of the head of the rail.

In Fig. 5 a modified form of rail is shown, 110 particularly adapted for this invention, with the flange 40 on the face 7 of the head which

connects the shoulder 22, a groove 41 being formed in this flange, the flange 32 being also provided with a lip 42 which engages in the groove 41 so that no lateral displacement is possible of the bridge 30. A similar flange 43 is rolled on the outwardly disposed face of the flange 9 of the rail which is also grooved on its upper side which is adapted to be engaged by the tongue 44 formed on the lower face of the bridging member 31.

It will readily be seen that by removing one of the bricks 35 any number of the adjoining bricks may be readily removed, and 15 the bridging plates 30 and 31 lifted out of engagement, entirely clearing the securing means and the accompanying connections to the rail uncovered by one or more sections of the bridge plates; thus expediting 20 the labor, time and period for which the track is exposed to danger from traffic, and preserving the edges of the adjoining paving intact, thus materially increasing the life time of the latter.

25 What I claim is:

1. A railway track construction, comprising a rail having supporting means thereon intermediate of its base and its tread, supports parallel with and forming an end 30 wall for the paving adjacent said rail, and a paving supporting plate carried on said supports and said supporting means on said rail.

2. A railway track construction, comprising 35 a rail supporting means, a rail supported thereon, a supporting means secured to said rail, a support mounted on said rail supporting means, forming an end wall for

paving adjacent thereto, and a bridging plate supported on said supporting means 40 on said rail and support intermediate of the paving surface and said rail supporting means adapted to support paving.

3. A railway track construction, comprising a cross tie, a rail having a plate supporting means intermediate of its tread and base mounted on said tie, a support spaced a distance from said rail on said tie, a plate bridging and supported on said support and said plate supporting means, and a removable paving medium supported on said plate. 45

4. A railway track construction, comprising a cross tie, a rail, a bracket secured to said rail on its sides intermediate of its tread and base, flanged plates engaging said bracket on said rail, and means to support the oppositely disposed portions of said flanged plates. 55

5. A railway track construction, comprising a cross tie, a flanged rail supported thereon, said flange being horizontally disposed on said rail intermediate of its tread and base, and a paving support provided with a horizontally disposed flange projecting from its rail face engaging said rail flange, 60 whereby a groove is formed between the adjacent side of the rail head and the flange supporting portion of the paving support. 65

In witness that I claim the foregoing I have hereunto subscribed my name this 70 day of October, 1912.

STERLING LEEO.
